FOLDING AND CONVERTIBLE TABLE
MECHANISM

Jacob R. Jones, Indianapolis, Ind.

Application June 29, 1931. Serial No. 547,589

4 Claims. (Cl. 273—4)

This invention relates to folding and convertible table mechanism and is particularly adapted for providing a number of game boards, pool and billiard tables and the like, or to serve as an ordinary library table, when no games are being played and one feature of the invention is the provision of convertible sections, the opposite faces of which are provided with games of various classes, so that by properly arranging the boards 10 any selected game may be played.

A further feature of the invention is the provision of means for attaching supporting legs to the table in a manner that will permit of the folding of the legs in line with the body portion 15 of the table, or be swung in a manner to invert the table top.

A further feature of the invention is the provision of means for locking the legs in their respective adjusted positions.

20 Other objects and advantages will be herein-after more fully set forth and pointed out in the accompanying specification.

In the accompanying drawings which are made a part of this application,

25 Figure 1 is a perspective view of one form of table with the inverted position of the legs shown in dotted lines.

Figure 2 is an enlarged detail sectional view as seen from line 2—2, Fig. 1.

30 Figure 3 is a sectional view as seen from line 3—3, Fig. 2.

Figure 4 is a perspective view of another form of table in set up position with parts broken out.

35 Figure 5 is a perspective view thereof, in folded position.

Figure 6 shows a modified construction to that shown in Figure 3, and,

Figures 7 and 8 are detail views of this modified construction.

40 Referring to the drawings in which similar reference numerals designate corresponding parts throughout the several views, the numeral 1 designates the body portion of a table which may be constructed in any suitable and conventional

45 manner, and 2 and 3 indicate boards having game features incorporated therewith and on opposite sides thereof, the board 2, in Fig. 1, being in representation of a pool table, but by inverting the board 2, a different game may be brought into 50 action or an ordinary flat top be provided.

The table proper is supported by means of legs 4, which are attached to the body 1 by means of plates 5 and 6, the plates 5 being attached to the body portion 1 by means of screws 7, while the 55 plates 6 are connected to the legs 4 by means of

screws 8. The plates are assembled in pairs, a pivot stud 9 being passed through each pair of plates so that the legs may be swung in an arc of a circle, to dispose them in folded relation with the body 1 or so swing the legs that the table 60 may be inverted. The plates 5 and 6 are provided with telescoping bearing rings 10 and 11, which provide a very stable union between said plates and hold the legs more or less rigid as well as serving to retain lubricant on the pivoting 65 parts.

Slidably mounted through the table legs 4 and the cooperating plates 5 and 6, are locking plungers 12, which enter casings 13 in the legs and are caused to move inwardly or outwardly by rotating 70 the plungers, each plunger having a pin 14 for engagement with a spirally arranged groove 15 in each casing 13, so that by rotating the plunger in one direction the inner end thereof will pass through registering openings in the plates 5 and 6 75 and lock them against pivotal action, and when rotated in the opposite direction, the end of the plunger will move out of engagement with the opening in the plate 5 and permit the leg to pivot.

By providing the faces of the boards with different game apparatus, a number of different games may be played by inverting the boards or the position of the legs with respect to the remainder of the table.

In Figs. 4 and 5, an ordinary table structure 80 16 is shown, and the legs 17 in this instance, are arranged to fold into alignment with the body portion 18, so that the table structure may be readily stored or carried through an opening of limited extent.

85 Referring to Figures 6, 7, and 8, it will be noted that the upper locking plunger 12 and sundry parts are omitted, the locking cam 19 being used instead. Said cam is pivoted to the upper part of the leg of the table by mounting 20, which is secured to the upper end of table leg by screws 21, and when the locking plunger 12 is in place, the locking cam 19 is rotated by means of its handle 22 into engagement with a tapering slot 23 in the overhanging portion of the table top, 90 said slot being positioned in said table top in relation to said cam so that as to thus clamp the table leg against the table body portion 18. The slot 23 is best provided by forming same in a metal strip and attaching same to the under surface of the overhanging table top, by means of screws 24 or the equivalent.

100 While the description and drawings illustrate in a general way certain instrumentalities which may be employed in carrying the invention into 110

effect, it is evident that many modifications may be made in the various details without departing from the scope of the appended claims, it being understood that the invention is not restricted to the particular examples herein described.

What I claim is:

1. A table mechanism having a normally vertical side wall structure, legs disposed exteriorly of said wall structure and serving to support 10 said mechanism, hinge mechanisms through which said structure is supported by the legs, and upon which said legs are swung from working position in either direction as desired, said hinge mechanisms comprising pairs of plates, pivot 15 stud means connecting the pairs of plates, and slidable plunger means for locking said plates in fixed relation with each other, as desired.

2. A table mechanism comprising a top, a normally vertical side wall structure embodied with 20 said top, legs positioned parallel to respective portions of said side wall structure, and exteriorly thereof, pairs of plates for securing each leg to said wall structure, pivot stud means connecting the plates of each pair, said stud means 25 serving as a pivot upon which said legs are swung in either direction as desired, independent telescoping circular parts carried by said plates between same, cooperating with said stud means in pivoting said legs, and means for locking said 30 legs in their adjusted positions.

3. A table mechanism, comprising a top portion, a body portion, comprising a normally verti-

cal side wall structure, legs exteriorly lapping said wall structure, serving to support said body portion and side wall structure, pairs of pivoted plates each of which serve to connect one of said legs to said side wall structure, plunger means serving to lock said plates against pivot action, said plunger means being associated with said plates a distance from the pivotal centers thereof, casings embodied with said legs through which said plungers pass, and means for degageably clamping each leg to said top portion, at a distance from the pivotal centers of said plates and on the other side thereof from said plunger means.

4. A table mechanism, comprising a body portion, having a normally vertical side wall structure, legs serving to support said body portion and side wall structure, pairs of pivoted plates each of which serve to connect one of said legs to said side wall structure, pivot means 90 serving to connect the plates of each pair, circular and telescoping bearing formations on the meeting faces of said plates, concentric with the pivotal centers thereof, and independent of said pivot means, plunger means normally below said 95 pivot means serving to lock said plates, against pivot action, casings embodied with said legs through which said plungers pass, and means for degageably clamping each leg to said body portion, normally above said pivot means.

JACOB R. JONES.
